UNITED STATES PATENT OFFICE

2,544,876

INSIGNE UNIT

David H. Bowder, Attleboro, Mass., assignor to
Swank, Inc., a corporation of Delaware

Application August 5, 1948, Serial No. 42,571

1 Claim. (Cl. 63—26)

1

This invention relates to an ornamental unit which may be mounted on any article of jewelry or attached to any personal article.

Many insignia units require that the complete unit for each letter of the alphabet be carried in stock in order that the initial of the person desiring personal identification may be had.

One of the purposes of this invention is to provide an identification unit which may be snapped into place in an article of jewelry, or other article of personal wear for ornamental or identification purposes, without the necessity of carrying the complete article in stock.

Another object of this invention is to provide a simple construction of unit which may be snapped into position and held in secure assembly with the body into which it is snapped.

Another object of this invention is to provide an arrangement so that when the unit is snapped into position it cannot be rotated about an axis within itself.

With these and other objects in view, the invention consists of certain novel features of construction, as will be more fully described and particularly pointed out in the appended claim.

In the accompanying drawings:

Figure 1 is a perspective view of a cuff link in which the insignia unit of this invention is assembled.

Figure 2 is a sectional view of a head portion of the link showing the insignia unit in position.

Figure 3 is a sectional view in a different plane from that shown in Figure 2.

Figure 4 is an exploded perspective view of the several parts of the unit and the mounting therefor.

In proceeding with this invention, I locate in a button like unit a resilient member, such as a spring, with its ends protruding from diametrically opposite sides of the button. This enables the ends to be forced inwardly and to be received in recesses in the walls of a cavity into which the button unit may be assembled.

With reference to the drawings, 10 designates a cuff link having one movable head 12 and a fixed head 13. The fixed head is on the end of a post 14 and comprises a circular mount 15, having a back wall 16, and undercut flanges 17. The insignia unit is designated generally 18 and is located in the cavity 19 formed by the flange 17, extending from the bottom wall 16. In one wall of this cavity, there is an opening, or recess 20, as shown in Figure 4.

2

The insignia unit, designated generally 18, comprises a member which may be of any shape to conform to cavity 19 and also sized to easily fit therein. In the present instance, this cavity is 5 circular and therefore the insignia member is also circular, comprising an annulus or ring 21 which is provided with an end or bottom wall or web 22. This annulus or ring is provided with diametrically opposite through opening 23, and 10 a spring designated 24 is positioned within the ring 22 by compressing it so that its end portion 25 will pass through the openings 23 and protrude beyond these openings a short distance. The top 26, which actually carries the insignia, is 15 then set into the annulus and is held in place by forcing the edge of the annulus 21 inwardly as 27 in Figure 2.

In use, it is merely necessary to place one 20 projecting portion 25 of the insignia unit into the cavity 16, and then by pressure, the other portion 25 of the spring will be moved inwardly and it will snap into the undercut of the annulus 21 so as to hold it in position. One end will find its 25 permanent location in the recess 20 in the wall of this cavity so as to prevent relative rotation of the mount 13 and the insignia unit 18.

I claim:

A selectively mountable unit comprising a perimeter with diametrically opposite radial 30 openings, spaced top and bottom walls closing said perimeter, a one-piece zig zag spring lying in substantially a single plane and located between said spaced walls to be guided thereby with its ends projecting in opposite directions through 35 said openings, said unit being adapted to be positioned into a recess with openings in its surrounding walls to receive the ends of the spring projecting through the perimeter of said unit.

DAVID H. BOWDER.
